UNITED STATES PATENT OFFICE.

BENJAMIN B. DAVIS, OF WILLIAMSTOWN, PENNSYLVANIA, ASSIGNOR OF ONE-HALF TO THOMAS B. DAVIS, OF SAME PLACE.

HAND ROCK AND COAL BORING MACHINE.

SPECIFICATION forming part of Letters Patent No. 301,049, dated June 24, 1884.

Application filed March 27, 1884. (No model.)

To all whom it may concern:

Be it known that I, BENJAMIN B. DAVIS, a citizen of the United States, residing at Williamstown, in the county of Dauphin and State 5 of Pennsylvania, have invented certain new and useful Improvements in Hand Rock-Boring Machines; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to coal-mining machines; and it consists in the construction, combination, and arrangement of the several parts, as will be hereinafter more fully described and claimed.

20 In the drawings, Figure 1 is a side view of machine. Fig. 2 is a detail view of the bearing-jaws and the hinged boxes. Fig. 3 is a detail view of the box-sections. Figs. 4 and 5 are detail views of the drill-shafts.

25 The supporting-beam A has its inner end formed on one side with teeth or projections A', and has a clamping section or bar, B, hinged to it near said end, as shown. This section is also provided with projections B', 30 similar to the projections A'. This beam and bar are inserted while in the position shown in Fig. 1 into a hole in the bank of coal, and the set-screw B² is turned through the beam against the bar and forces said parts into the position 35 indicated in dotted lines, Fig. 1, and the supporting-beam will be firmly secured in position.

The jaws C C are provided in their upper ends with bearings C', and have their lower 40 ends connected by plate C². This plate is provided with a depending stud or shaft which is journaled in the supporting-beam, as shown. It permits the bearing-jaws to be swung horizontally in order to adjust the drill 45 to any desired position. A bracket, D, is mounted on the plate C², near its forward edge, and serves as a bearing for the set-bolt D', which will be hereinafter described.

The box E is composed of the sections E' 50 E², each of which is provided with a semi-

circular threaded bearing or recess, and with an upwardly-projecting arm or bar, E³. One of the bars is provided with a stud, E⁴, which, when the box is closed, fits in a corresponding recess in the other bar, as will be understood from Figs. 2 and 3. The section E' is provided with lugs F F', depending from its lower side. The rear lug, F', is the longer of the two, and is formed with a slot, F², in its lower end. The section E² is also provided 55 with a depending lug, F³, which fits between lugs F F', and is pivoted thereto by pin F⁴, as clearly shown. Where so desired, the lug F may be dispensed with; but I prefer to use it, as a firmer bracing of the parts is thereby 60 had. I provide each of these sections with a trunnion, G, which is journaled in the bearings C, as clearly shown in Fig. 1. The bolt D' is reduced in size at D², near its rear end, forming a shoulder, D³. The contracted portion D² is inserted through slot F², and the shoulder D³ bears against the forward side of lug F'. A nut, D⁴, is turned on the end of portion D² up against the rear side of lug F'. Now it will be seen that, by turning bolt D', the 65 boxing can be tilted to any desired angle to the horizontal and secured. The adjusting-bolt, being arranged on the base of the bearing-jaws, turns therewith, and is consequently at 70 all times in position for operation.

The feed-screw H turns through the boxing E. When it is desired to place this screw in position, the boxing is opened, as shown in Fig. 2, and the screws placed down therein. The bars E³ are then pressed together, as indicated in dotted lines, Fig. 2, and the ring or collar E⁵ is slipped down thereover, securing the sections of the boxing firmly together, as will be understood. At the forward end of the feed-screw I form a socket, H', into which 75 is fitted the tenons I' on the drill-shaft I. These shafts may be made of different lengths and used as desired, replacing longer for shorter ones until the hole has been drilled the desired depth. A bar, J, is secured on the 80 rear end of the feed-screw, and at right angles thereto. This bar is provided with keepers or loops J'. The crank-handle K has its bar K' passed through these keepers, and is secured to the bar J by set-screw K², by loos- 85

ening which the crank may be set longer or shorter, as desired.

The operation of my machine is simple, and will be readily understood from the description before given.

The drill-shaft I is provided at its forward end with a bit, J. This bit is formed with the four corners $j j' j'' j'''$, and is bifurcated by a slot, as shown. This bit, I have found, cuts 10 easily and greatly reduces the wear on the machine, enabling the latter to be made much lighter, and consequently less expensive, as will be appreciated.

Having thus described my invention, what 15 I claim, and desire to secure by Letters Patent, is—

1. In a mining-machine, the combination of the feed-screw, the threaded barrel or boxing pivotally supported in suitable bearings, and 20 provided with a depending lug or bracket, and a set-bolt turning through a threaded support, and adapted to engage said lug or bracket and adjust the boxing on the journals or bearings thereof and secure the said boxing in any desired position, substantially as 25 set forth.

2. The combination, in a mining-machine, of the base-plate provided with bearing-jaws C, and bracket D, the feed-screw, the threaded

barrel composed of section E, having lug F', 30 provided with slot F'', and section E'', having lug F''' pivoted to lug F', the said sections having upwardly-projected bars E'', the collar E'', adapted to embrace bars E'', and the set-bolt D', turned through bracket D, and having a 35 contracted portion, D'', on its rear end inserted through slot F'', and the nut D', all constructed and adapted to operate substantially as set forth.

3. The mining-machine, substantially as 40 herein described and shown, composed of a supporting-beam, the bearing-jaws connected by base-plate C, journaled on the supporting-beam and provided with bracket D, the sectional boxing provided with depending lug 45 F', having slot F'', the set-bolt D', the feed-screw turning through the boxing, and provided at its rear end with bar J, having loops or keepers J', the crank-bar K, passed through said loops or keepers, and the clamping-screw 50 K', all as and for the purposes specified.

In testimony whereof I affix my signature in presence of two witnesses.

BENJAMIN B. DAVIS.
